UNITED STATES PATENT OFFICE

110,160

DESIGN FOR AN ASHTRAY

Frank Truttman, Los Angeles, Calif.

Application March 24, 1938, Serial No. 76,077

Term of patent 7 years

To all whom it may concern:

Be it known that I, Frank Truttman, a citizen of the United States, residing at Los Angeles, in the county of Los Angeles and State of California, have invented a new, original, and ornamental Design for an Ashtray, of which the following is a specification, reference being had to the accompanying drawing, forming part thereof.

The figure is a perspective view of an ashtray, showing my new design.

I claim:—

The ornamental design for an ashtray, as shown.

FRANK TRUTTMAN.
